UNITED STATES PATENT OFFICE.

ELIOT KEEN, OF NEW YORK, N. Y., ASSIGNOR TO PICTURADIO CORPORATION, A CORPORATION OF NEW YORK.

METHOD AND SYSTEM FOR TRANSMITTING PICTURES TO A DISTANCE.

Application filed June 13, 1922. Serial No. 567,936.

To all whom it may concern:

Be it known that I, ELIOT KEEN, a citizen of the United States, residing in the borough of Manhattan, city, county, and State of New York, have invented certain new and useful Improvements in Methods and Systems for Transmitting Pictures to a Distance, of which the following is a specification, reference being had to the accompanying drawings, forming a part thereof.

My invention relates to a method and system for transmitting pictures to a distance.

The object of the present invention is to produce a system of this character in which pictures may be rapidly transmitted and in which the transmission is accomplished through the agency of wireless signals.

In its preferred embodiment and most important aspects, the invention is practiced in substantially the following manner:

The picture to be transmitted is first copied or photographed on a zinc or other suitable plate on which either the dark or the light portions of the picture are distinguished from the rest by the occurrence of closely and evenly spaced corrugations, in relief or sunken, as may be most convenient. This plate may be prepared in accordance with any one of a number of lithographic or photographic or etching or engraving methods well known in the respective arts.

The processes used in preparing so-called half tone plates are almost directly applicable. Thus, preferably, the picture is photographically copied through a screen or several screens, whereby the picture is finally reproduced on a zinc plate or the equivalent, being also divided into a plurality of bands, and whereby again within each band the varying degrees of light or shade are represented by groups of closely spaced corrugation lines (raised or sunken, as convenient), the number of lines per group representing the intensity of light or shade.

This will give in the last analysis a picture composed entirely of fine sunken (or raised) parallel lines, all of substantially the same width and spacing, but varying in length and grouping. This form, the preferred one, but which may be infinitely varied without departing from the spirit of this invention, leaves the final plate used for transmission a mere series of fine corrugations on even centers and of varying length. The bands re-

ferred to have in this embodiment no final tangible existence as such, being merely successive groups of lines or of spaces where lines might be. Thus, in dark areas of the picture, assuming numerical groupings as shown on the drawings, a band would comprise seven fine lines; in areas a little less dark, five, centrally located; in gray areas, three; in light areas, one fine line; and in white areas, no lines at all.

It will be clear that the choice of the above numbers is arbitrary, as is also the direction of the lines. They might be laid across the bands, or diagonally. The concept of bands may be entirely omitted and the picture reproduced in fine parallel lines subject to no arbitrary grouping. Or fine squares may replace the fine lines, or an endless number of variations well known in the half tone and allied arts may be used without departing from the spirit of my invention.

For fulfilling the purposes of my invention, any plate having corrugations as fine lines or areas on regular centers, whether in relief or sunken, will be suitable except that the corrugations transmit best when all are of equal value. In other words, by the means disclosed or by any other means in accordance with the spirit of this invention, it is not as easy to transmit individual values of individual corrugations as values of groups of similar corrugations. The groups need not, as pointed out, be regular. This statement is only relatively true. Individual values can be transmitted. These statements will become clear in the light of the further means employed.

In accordance with the preferred embodiment of my invention, the transmitting plate or record is crossed at right angles to the corrugations or lines by the stylus of a phonographic reproducer and will cause the production of sounds. The corrugations in a group are preferably close enough to each other to cause the vibration of the diaphragm of this reproducer and the generation of an audible sound. As the reproducer successively co-operates with the various groups or bands, preferably by causing the record or plate to rotate on a drum under the reproducer, sounds all of a definite pitch will be produced, each sound representing a continuous area of dark or light. When repeated short sounds are separated from each

other by a silent period, black interspersed with white is being sent, and the light or shade value depends upon the relative length of sound and silent period. The pitch of all 5 sounds is preferably the same. The depth and width of individual corrugations affects the intensity of the sound somewhat, and it will be clear later, from a consideration of the reproducing means, that this affords a 10 means of varying somewhat the light of shade of the received picture, i. e., of transmitting some individual value of individual corrugations.

This reproducer is associated with a system 15 through which electric waves, preferably of audio frequency, may be transmitted. Either the usual line wire telephone system or a radio telegraph or telephone transmission system may be used for this purpose.

20 The latter alone will be discussed.

To any one skilled in the art it will be obvious what modifications of apparatus would be required for transmission by wires.

The vibrations of the phonograph reproducer diaphragm are used for modulating 25 the frequency of the radio carrier waves, either by means of the actual sound waves caught in a separate telephone transmitter or by means of a telephone transmitter 30 forming part of the reproducer. Either method results in modulating the continuous or carrier wave, whose length may be as required by the accidents of sending station, commercial conditions, etc., by trains of 35 audio waves, all audio waves being of the same length. To some extent, as pointed out, the individual waves of these trains may vary in amplitude, i. e., in strength, and the number of waves in a train, and the 40 length of the trains will vary constantly according to the picture being transmitted.

It will be obvious to those skilled in the art that instead of thus differentiating between the black and white parts of a picture, the system may be modified without departing from the spirit of my invention by transmitting signals in which a certain pitch 45 represents the black and a certain other pitch rather than silence represents the 50 white parts of the picture.

All the above described apparatus is at the sending station. The receiving station comprises in addition to the usual equipment for line telephone or wireless telephone 55 receiving stations, a device responsive to the modulated current impulses generated at the transmitting station. This responsive device comprises a sensitive element vibrated by the audio waves in front of an aperture through 60 which a beam of light may be transmitted to a light-sensitive film. While vibrating, this element does not visibly obstruct the passage of the light ray. When, however, the element is not vibrated by audio modulations 65 of the carrier wave, it comes instantly to rest

temporarily, obstructing the passage of the light ray through the aperture. A light-sensitive film rotates within a chamber, and back of said aperture, at a speed corresponding to that of the plate or picture at the 70 sending station. Both the sending plate and the receiving film are traversed longitudinally while rotating after the manner of a phonograph cylinder. The result will be the printing by the ray on the sensitized film of dark lines corresponding to corrugated areas of the plate at the sending station.

In order to insure synchronism between the sending and receiving stations, suitable 75 "stop and start," or other synchronizing means must be provided. Any of the well known synchronizing means used in printing telegraphy may be adapted for the purpose.

The drawings represent a preferred embodiment of my invention. Fig. 1 is an elevation, partly in section of the sending cylinder and reproducer; Fig. 2 is a sectional view of the same cylinder and phonographic reproducer, showing also a telephone transmitter; Fig. 3 is an enlarged detail view of a portion of the developed surface of the sending plate; Fig. 3^a shows a negative from which the plate of Fig. 3 is prepared; Fig. 4 shows the receiving galvanometer and an end view of the receiving cylinder; Fig. 5 is an elevation of the receiving cylinder together with a sectional view of the driving control; Fig. 6 shows the sending circuit with a sectional view of the microphonic reproducer; Fig. 7 shows the receiving circuit; and Fig. 8 shows a modified receiving circuit.

The sending apparatus is mounted on a table 1 and consists of a sending record or plate 2 which is held around a cylinder 3 by a suitable clamping means such as rings 4. The cylinder 3 is fixed to a horizontal shaft 5. One end of the shaft 5 passes through a pulley wheel 6 rotatably mounted in suitable bearings 7. The pulley 6 is keyed to the shaft 5 with a long key-way 6^a whereby the shaft may be horizontally displaced. One end of shaft 5 is screw-threaded at 8 and cooperates with a stationary support and half-nut 9 in such a manner that, in response to each complete revolution of the shaft 5, the shaft and the cylinder 3 will be displaced by one step in a right-hand direction (Fig. 1).

A sound reproducing device 10 is carried on the table 1 at 11 in such a manner that its stylus 12 cooperates with the plate 2 and passes across this plate at intervals determined by the lead of the thread 8. A lever 13 (Fig. 2) carrying the stylus is pivoted at 14 to the relatively heavy floating plate 15 pivoted on the fixed casing 16. The stylus 12 is carried at one end of this lever 13, the other end of the lever being connected with

one end of a link 17. Link 17 protrudes through an aperture 18 in the plate 15, and its other end is fixed at 19 to a diaphragm 20 clamped in the casing 16. The diaphragm 20 is surrounded by a horn 21, and the sound vibrations produced thereby may actuate a telephone transmitter 22.

The reproducer diaphragm 20 is vibrated by means of the plate 2 which acts as a phonographic cylinder record of the hill and valley type. The hills on this record are indicated by the black lines 30 and the valleys by the white spaces, or vice versa. If Fig. 1 of the drawings is turned around so that the screw-threaded end 8 of shaft 5 points towards the reader, it will be seen that the picture obtained by the black and white combination represents the profile of a man, the representation being composed of black lines 30 of varying widths. Obviously, it is a matter of convenience or choice whether the picture is defined by black lines on white, or vice versa.

Referring now to Fig. 3, it will be seen that each one of the heavy black lines 30, which were referred to as bands, is actually composed of a plurality of black lines representing the corrugations above referred to.

The picture to be reproduced is first enlarged on a film or transparent plate, is then printed through a relatively coarse screen or grating having substantially equal open barred stripes, and held at some distance from the sensitized film. The object is to convert the varying degrees of light of the original enlarged film into stripes of developed emulsion of varying widths. Fig. 3^a shows, much enlarged, a minute part of a film thus obtained. This is according to principles of the well-known half-tone process, except that the screen is a one-way screen and not divided into squares. The film illustrated in Fig. 3^a is printed preferably on a sensitized zinc plate through a second one-way screen seven times as fine as the first, and with the film and screen held close to the plate. The object is to convert the white areas of Fig. 3^a into areas of closely spaced lines 30^a, as illustrated on Fig. 3. It will be observed that Figs. 3^a and 3, though of different appearance, actually define the same outline and light values.

The developed zinc plate is preferably coated with dragon's blood, or by other chemical means so treated that a slight difference of level is obtained between the light struck areas and the others. This results in a plate suitable to co-operate with a phonographic reproducer.

The top edge of the zinc plate (Fig. 3) is provided by chemical or mechanical means with a band of corrugations 31 more widely spaced than the corrugations 30^a. The lower edge of the plate is left blank for a suitable margin 31^a.

Instead of the usual sound producing phonographic reproducer 10, a microphonic reproducer of any suitable type such as the one shown in Fig. 6 may be provided to respond to the vibrations of the stylus 12 when actuated by the corrugations of the surface of plate 2. In this case, the lever 13 and rod 17 are actuated by the stylus 12 to transmit the vibrations to a telephone transmitter diaphragm 40 clamped in the casing 16. The diaphragm 40 carries a transmitter button composed of front and rear electrodes 41 and 42 and a carbon granule chamber 43. The electrodes and carbon granule chamber are included in a circuit comprising also conductors 44. The resistance of this circuit is varied in the well known manner in response to the compression and dilation of the carbon granule chamber 43.

The apparatus at the receiving station is illustrated in Figs. 4, 5 and 7. This apparatus is mounted on a table 100 and comprises a film chamber 101, a string galvanometer 102, and a source of light 103. The galvanometer field is maintained by a suitable local current supply through the agency of coils 104. The pole pieces 105, 106 are perforated at 107, 108. A conducting string 109 is stretched between the two pole pieces. The beam of light passing through the perforations 107, 108, is suitably restricted by a small diaphragm 110 having a minute aperture. While the string 109 is vibrating, the light rays coming from source 103 are not visibly impeded. These light rays are focused to pass in parallel lines through perforation 107 by means of convex and concave lenses 111, 112 suitably positioned in a holder 113. When leaving perforation 108, the light rays are again focused by means of a convex lens 114 to pass through an opening 115 in the side wall of chamber 101 and strike against a roll of light-sensitive film 116 fastened to a cylinder 117 by means of hoops 118. Depending on the characteristics of the wave trains traversing the string 109, the periods of its vibration and rest will be varied and to some extent its amplitude. During the periods of rest, the string will prevent the passage of light through diaphragm 110 since the opening therein, which is preferably a longitudinal slit parallel with the string, is completely covered by the string at rest. It will be obvious from the above that, the greater the amplitude of the string vibration, the more rapidly the string will pass over the slit, and that thus the amount of light admitted in a given time can be somewhat varied by the strength of the received waves.

As stated above, this furnishes means whereby individual values (depth of etching, etc.) of the fine corrugations on the sending plate can be reproduced on the received picture.

The cylinder 117 carrying the light-

sensitive film is mounted within the casing 101 on a horizontal shaft 120 supported in suitable bearings on the table 100. The chamber 101 is provided with wheels 121 which rest on tracks 122 secured to the table 100. The cylinder 117 together with the chamber 101 is keyed to the shaft 120. The power of a motor 123 is transmitted through a belt 124 to a pulley wheel 125, the hub 126 of which is loosely mounted on shaft 120. The inside flange of the pulley wheel 125 is bevelled and co-operates with a cone-shaped clutch 127 keyed to the shaft 120 at 128, the key-way 129 being relatively long to permit the horizontal displacement of the shaft 120 and cylinder 117. The clutch 127 is normally held in frictional engagement with the driving wheel 125 by means of a coiled spring 130. An electro-magnet 131 fastened to the table 100 may be operated to withdraw and grip the clutch 127 from engagement with the wheel 125 against the action of the spring 130 for arresting the rotation of the shaft 120. Keyed to the shaft 120 with the long key-way 129 are interrupters 132, 132^a, 132^b and cam 133. By means of their conducting segments 134, 134^a and 134^b, the interrupters 132, 132^a and 132^b control the closing of circuits terminating in wipers 135, 135^a and 135^b, and by means of a projection 136, the cam 133 may cause the closure of a circuit including contact springs 137 which normally tend to separate. One end of the shaft 120 is screw-threaded at 140 and co-operates with a half-nut 139 in such a manner that, in response to one complete revolution of the shaft it will cause the horizontal displacement by one step. The cylinder 117 is preferably smaller than the cylinder 3, because for mechanical reasons the corrugated sending plate 2 is larger than the usually required size of the received picture. In order to insure the proper time relation between the rotations of cylinders 3 and 117, which time relation must be very accurately maintained if the received picture is not to be distorted, means to produce synchronous or isochronous revolution of the two cylinders must be provided. Any such system well known in printing telegraphy and the allied arts may be readily adapted for the purpose. In the present embodiment, a form of the so-called "stop-start" system is disclosed. This comprises means related to the sending cylinder to generate a starting pulse or tone, preferably distinguishable from other pulses or tones; means to transmit this pulse to the receiving station, which in the present case are identical with the transmitting means for the picture-identifying pulses; control means at the receiving station, operated by the starting pulse, to set in motion the receiving

cylinder; and means to bring the receiving cylinder to rest after one revolution always in the same position.

The starting pulse or tone is generated by the corrugations 31 on the plate 2, which, being on different (larger) spacing from the corrugations 30^a, generate a wave train of different (lower) frequency from the picture wave trains.

The control means shown in Fig. 7 comprises a permanent magnet 150 provided with soft iron pole pieces carrying energizing coils 151. Opposite the pole pieces of the magnet 150, an iron diaphragm 152 is loosely supported on three rest points 152^a, preferably located on the nodal ring of the diaphragm. The diaphragm must have such diameter and thickness as to have a fundamental period like that of the starting wave-train. A contact 152 pivoted on a fixed support 154 rests with its own weight on a contact point 153^a in the center of the diaphragm. These contacts control a circuit comprising a resistance 155, a marginal relay 156 and a source of electrical current 157. The contacts of relay 156 control a circuit comprising the cam contacts 137, a source of electrical current 158 and the clutch magnet 131.

The operation of the system in transmitting a picture is as follows:

Let us assume that the receiving station is in its normal position of rest, and that the sending cylinder 3 is rotating in the direction of the arrow (Figs. 2 and 3).

The first result of the motion of the sending cylinder is that the stylus encounters the corrugations 31. While riding over corrugations 31, the carbon button 43 is subjected to a vibratory pressure and produces a train of waves corresponding to corrugations 31 which will be referred to as the starting note.

As shown in Fig. 6, this train of waves is used to modulate the carrier wave of a continuous wave transmitting system. The electrical and mechanical means used for these purposes form no part of the present invention, which is applicable to any known or possible radio telephone system. Fig. 6 shows a simple standard circuit that may be used, and a further explanation of which will be dispensed with.

The starting note on its carrier wave is received on a receiving antenna circuit (Fig. 7), passes through a radio frequency amplifier, is rectified in a detector circuit, and then passes through, if desired and as shown, an audio frequency amplifier from which it is repeated as an alternating current wave train by the audio transformer secondary 160, in a circuit comprising conductor 161, brushes 135^a, conducting segment 134^a on which the brushes are resting, conductor 162, magnet coils 151, conductor 163, and 130

back to transformer secondary 160. The speed of the sending cylinder is such that the pitch of the starting note is the fundamental of diaphragm 152. The starting note, therefore, sets the latter into vibration. At this time relay 156 is energized through the following circuit: battery 157, diaphragm 152, contacts 153^a, contact member 153, support member 154, high resistance 155, the winding of relay 156, and back to battery 157. The value of resistance 155 is such that the relay is very weakly magnetized. The vibration of diaphragm 152 will break this circuit, whereupon relay 156 instantly drops its armature and opens the energizing circuit of clutch magnet 131 which until now has been energized. The de-energization of this magnet (Fig. 5) releases the clutch 127 which engages pulley-wheel 125 and sets shaft 120 and cylinder 117, interrupters 132, 132^a, 132^b and cam 133 in motion.

At the sending station the stylus next encounters the corrugations 30^a and, as described in the case of corrugations 31, wave trains of a somewhat higher frequency and lengths, as determined by the sending plate, are generated and received. By this time, due to the rotation of shaft 120, the interrupters are in such position that the circuit from transformer secondary 160 through conductor 161 is no longer closed through wipers 135^a, but through wipers 135^b, segment 134^b, conductor 164, resistance 165, string 109, conductor 163, and back to transformer secondary 160. String 109 responds to the wave trains and light is admitted to the film 116 on the receiving cylinder 117 in quantity and duration as determined by the strength and length of the wave trains. Light is prevented access to the film for times corresponding to the passage of the sending stylus over blank areas of plate 2.

The speed of the motors driving the sending and receiving cylinders must not vary materially or the received picture will be distorted. Clearly, the speed of the receiving cylinder is slightly higher than that of the sending cylinder for the latter rotates continuously, whereas the receiving cylinder starts from rest, rotates during the transmission of picture wave trains, stops and awaits the starting note, repeating this cycle for every revolution of the sending cylinder. The stopping of the receiving cylinder occurs as follows:

After the stylus has traversed all corrugations 30^a and has entered upon blank margin 31^a of plate 2, at the receiving station, conducting segment 134 makes contact with brushes 135. A circuit is now closed from battery 157, winding of relay 156, brushes 135 and segment 134, and back to battery. Relay 156 is energized and prepares the circuit of the clutch magnet 131. At this

time the circuit of magnet 131 is open at contacts 137. As interrupter 132 revolves further, left-hand wiper 135 breaks contact with segment 134 and opens the short circuit thereby originally afforded around resistance 155. Relay 156 remains up, being feebly energized through the above traced circuit including diaphragm 152 which by this time has come to rest. In this connection, it should be noted that diaphragm 152 has not been responding to the picture transmitting wave trains which are of higher frequency than its fundamental. 75

Clutch magnet 131 remains de-energized and shaft 120 continues to rotate until cam 133 closes the contact 137 by its point 136, thereby completing the circuit from battery through contacts 137, front contact and armature of relay 156, clutch magnet 131, and back to battery. Clutch magnet 131 withdraws clutch member 127 from pulley 125 and grips it, stopping it instantly. 85

This cycle of operations is repeated for every revolution of the sending plate until the whole picture is transmitted. The sending and receiving cylinders having been horizontally displaced by their screw-thread, are reset by hand before sending any further pictures. 90

The film 116 must, of course, be developed and fixed like any other photograph. 95

Fig. 8 shows a modified form of synchronizing system. If this system is used instead of the one shown in Fig. 7, the circuit leading to the string 109 includes only resistance 165 and the transformer secondary 160. The receiving circuit used is identical with that shown in Fig. 7 as far as the transformer 160. The transformer used in the present case has two secondaries 160 and 170. 100

The transformer secondary 170 is the input of an audio rectifier tuned to the frequency of the starting note by means of condenser 171. The output of this circuit is pulsating audio frequency current which traverses the left-hand or knockdown winding of relay 156^a. The relay 156^a is feebly energized through its right-hand winding by battery 157 through resistance 155. The pulsating current in the left-hand winding is sufficient to de-energize this relay which opens the circuit of clutch magnet 131 in exactly the same manner as explained in connection with Fig. 7. The re-energization of the relay is controlled by 110 interrupter 132 in the above-described manner. 115

As will be understood from the preceding description, the speed limitations are in the present embodiment practically those of the light-interrupting element. In practical operation the rate of vibration of this element may approach or even exceed the limits of audio frequency. Depending on the detail desired in the picture, such rate 125 130

in terms of the described picture transmission method may represent a value equivalent to upward of twenty square inches of received picture area per minute.

5 Where the term **audio frequency** is employed herein, it is to be understood as comprehending frequencies of super **audibility**; and where the phrase **wave-trains** is used, it is to be understood as comprehending the 10 possibilities of a train comprised of a single wave.

In the means selected for illustration as the preferred form of my invention, I have shown those now believed by me to be best 15 adapted for attaining the stated objects of my invention, but such means are themselves susceptible of a wide range of modification without departure from the spirit of my disclosure.

20 I believe my invention, as above described, to be broadly novel, both as to the methods involved and the range of possible physical embodiments thereof. Since the physical means of practice of my method are capable 25 of expression in a great variety of structural forms, I do not intend to be understood as limiting the scope of my disclosure by any particular description thereof contained in the specification.

30 What I claim is:

1. The method of picture transmission consisting in preparing a plate on which every area, graduation and outline of a picture is represented by corrugations and 35 blank spaces, producing sound currents representing the corrugations, transmitting the sound currents, receiving the sound currents, and finally converting the sound currents into light variations.

40 2. The method of picture transmission consisting in producing waves of certain characteristics representing predetermined parts of a picture, and waves of certain other characteristics representing points 45 outside of the picture.

50 3. The method of picture transmission consisting in producing waves of certain frequency representing predetermined parts of a picture, and waves of certain other frequency representing a margin line of the picture.

55 4. The methods of picture transmission consisting in producing waves of certain audio frequency representing predetermined parts of a picture, and waves of certain other audio frequency representing a margin line of the picture.

60 5. In a picture transmission system, a plate on which a picture is represented by corrugations and blank spaces, means for producing sound currents representing the corrugations, means for transmitting the sound currents, means for receiving the sound currents, a light-sensitive film, a 65 source of light, and means controlled by the

received sound currents for admitting light to said film.

6. In a picture transmission system, a plate on which every area, graduation and outline of a picture is represented by corrugations and blank spaces, means for producing sound currents representing the corrugations, means for transmitting the sound currents, means for receiving the sound currents, a light-sensitive film, a source of light, 75 means controlled by the received currents for admitting light to said film.

7. In a picture transmitting system, an audio wave producing device variably operable in accordance with the dark and light 80 portions of a picture, a device responsive to the audio waves, a light-sensitive film associated with the said responsive device, and means controlled by the said responsive device for varying the amount of light that 85 may reach the said film.

8. In a picture transmission system, a transmitting plate, corrugations thereon to distinguish certain areas of said plate, different corrugations to distinguish certain 90 other areas on said plate, a phonographic element operable by said corrugations, a telephonic element responsive to the operation of said phonographic element, means including said telephonic element for generating electrical waves of different frequencies, a device responsive to the waves representing said certain areas of said plate, a movable film of light-sensitive material, a source of light, means controlled by the 100 said responsive device for varying the amount of light admitted to said film, another device responsive to the waves representing the said certain other areas of said plate, and means controlled by said other device for controlling the moving of said film. 105

9. In a picture transmission system, a transmitting plate, corrugations thereon representing the black parts of the picture, different corrugations thereon representing 110 the margin line of said picture, a phonographic element operable by said corrugations, a telephonic element responsive to the operation of said phonographic element, means including said telephonic element for 115 generating electrical waves of a relatively high frequency when said phonographic element is actuated by the first-mentioned corrugations and electrical waves of a relatively low frequency when said phonographic element is actuated by said second-mentioned corrugations, a device responsive 120

125 to the high frequency waves, a movable film of light-sensitive material, a source of light, means controlled by said responsive device for varying the amount of light admitted to said film, another device responsive to the low frequency waves, and means controlled by said other device for controlling the moving of said film. 130

10. In a picture transmission system, a transmitting plate, corrugations thereon to distinguish certain areas of said plate, different corrugations to distinguish certain other areas on said plate, a phonographic element operable by said corrugations, a telephonic element responsive to the operation of said phonographic element, means including said telephonic element for 5 the margin line of said picture, a phonographic element operable by said corrugations, a telephonic element responsive to the operation of said phonographic element, means including said telephonic element for 10 generating electrical waves of a relatively high frequency when said phonographic element is actuated by the first-mentioned corrugations, and electrical waves of a relatively low frequency when said phonographic element is actuated by said second- 15 mentioned corrugations, a device responsive to the high frequency waves, a movable film of light-sensitive material, a source of light illuminating said film only when said responsive device is operating, another device 20 responsive to the low frequency waves, and means controlled by said other device for controlling the moving of said film. 11. In a picture transmission system, a 25 transmitting plate, relatively fine corrugations thereon representing the black parts of the picture, relatively coarse corrugations thereon representing the margin line of said picture, a phonographic element operable by said corrugations, a telephonic element responsive to the operation of said phonographic element, means including said telephonic element for generating electrical waves of a relatively high frequency when 30 said phonographic element is actuated by the fine corrugations, and electrical waves of a relatively low frequency when said phonographic element is actuated by the coarse corrugations, a device responsive to 35 the high frequency waves, a movable film of light-sensitive material, a source of light, means controlled by the said responsive device for varying the amount of light admitted to said film, another device responsive to the low frequency waves, and means controlled by said other device for controlling the moving of said film.

12. In a picture transmission system, a picture representing medium, indicia thereon to distinguish certain areas thereof, a phonographic element operable by said indicia, a telephonic element responsive to the operation of said phonographic element, means for generating waves, means for 40 modulating said waves by the telephonic element, a device responsive to the modulated waves, a movable film of light-sensitive material, a source of light, means controlled by said responsive device for varying the amount of light admitted to said film, another device responsive to the low frequency waves, and means controlled by said other device for controlling the moving of said film. 13. In a picture transmission system, a 45 transmitting plate, corrugations thereon to distinguish certain areas of said plate, different corrugations to distinguish certain other areas on said plate, a phonographic element operable by said corrugations, a telephonic element responsive to the operation of said phonographic element, means for generating electrical waves, means for modulating said waves by the telephonic element, a string galvanometer responsive to the modulated waves representing said certain areas of said plate, a movable film of light-sensitive material, a source of light, means controlled by said string galvanometer for varying the amount of light admitted to said film, a device tuned to the modulated waves representing the said certain other areas of said plate, and means controlled by said device for controlling the moving of said film. 14. In a picture transmission system, a transmitting plate, corrugations thereon to distinguish certain areas of said plate, different corrugations to distinguish certain other areas on said plate, a phonographic element operable by said corrugations, a telephonic element responsive to the operation of said phonographic element, means for generating electrical waves, means for modulating said waves by the telephonic element, a string galvanometer responsive to the modulated waves representing said certain areas of said plate, a movable film of light-sensitive material, a source of light, means controlled by said string galvanometer for varying the amount of light admitted to said film, a device tuned to the modulated waves representing the said certain other areas of said plate, and means controlled by said device for controlling the moving of said film. 15. In a picture transmission system, a transmitting plate, corrugations thereon to distinguish certain areas of said plate, different corrugations to distinguish certain other areas on said plate, a phonographic element operable by said corrugations, a telephonic element responsive to the operation of said phonographic element, means for generating electrical waves, means for modulating said waves by the telephonic element, a device responsive to the modulated waves representing said certain areas of said plate, a movable film of light-sensitive material, a source of light, means controlled by said responsive device for varying the amount of light admitted to said film, another device responsive to the modulated waves representing the said certain other areas of said plate, means controlled by said other device for controlling the moving of said film, and means controlled by the moving of said film for rendering said devices successively operable.

16. In a picture transmitting device, a

- plate prepared from a picture having corrugated and smooth areas to represent different light values of the picture, and a corrugated area representing the margin line of the picture.
17. In a picture transmitting device, a plate prepared from a picture having finely corrugated areas and smooth areas to represent different light values of the picture, and a coarsely corrugated area representing the margin line of the picture.
18. In a picture transmitting device, a plate prepared from a picture having finely corrugated and smooth areas representing different light values of the picture, a coarsely corrugated area representing one and a smooth area representing another margin line of the picture.
19. The method of making plates for transmitting pictures which consists in first copying the picture on a plate by representing certain areas of the picture as relatively coarse dark and light lines, and certain other areas as light areas, copying the imprint thus obtained on a second plate by representing the light areas as areas of relatively fine lines, and the dark areas as blank spaces.
20. The method of making plates for transmitting pictures which consists in first
- copying the picture on a plate in the form of relatively wide dark and light bands, copying the imprint thus obtained on a second plate in the form of bands of relatively fine dark and light lines.
21. The method of making plates for transmitting pictures which consists in first photographing the picture on a sensitized plate through a relatively coarse screen held at a distance from the sensitized plate, and photographing the imprint thus obtained on a second sensitized plate through a relatively fine screen held close to the plate.
22. The method of making plates for transmitting pictures which consists in first photographing the picture on a sensitized plate through a relatively coarse one-way screen held at a distance from the sensitized plate, photographing the imprint thus obtained on a second sensitized plate through a relatively fine one-way screen held close to the plate.
23. The method of making plates for the transmission of pictures in which the various light values of the picture are first represented by dark and light lines of various width, and then these lines are subdivided into dark and light lines.

ELIOT KEEN.
